His Attorney.

UNITED STATES PATENT OFFICE

SIGWART RUPPEL, OF FRANKFORT-ON-THE-MAIN, GERMANY

SWITCH

Application filed September 22, 1930, Serial No. 483,634, and in Germany September 26, 1929.

My invention relates to switches, more especially of the kind disclosed and claimed in my copending application for Letters Patent of the United States, Serial No. 217,438, filed September 3, 1927, for method and apparatus for interrupting high tension circuits on which the present invention is an improvement.

It is an object of my invention to combine a switch of this type with a disconnecting or isolating switch so that the two switches form a unit.

It is a further object of my invention to provide a connection between the compressed gas or gas blast switch and the disconnecting or isolating switch in such manner that the switches are locked with respect to each other so that the disconnecting switch can be opened or closed only if the compressed gas switch is in its open position.

It is a further object of my invention particularly in a multiple phase switch to ground the switch contacts when the movable contacts of the disconnecting switch reach their open or isolating position whereby the blades of the disconnecting switch connect the contacts of the compressed gas switch in series and to ground.

In the drawing affixed to this specification and forming part thereof some embodiments of my invention are illustrated by way of example.

In the drawing

Fig. 1 is a diagrammatical side elevation, partly in section, of a switch or circuit breaker according to my invention.

Fig. 2 is a plan view of the switch shown in Fig. 1.

Fig. 3 is a side elevation partly in section of another embodiment of my invention.

Figs. 4 and 5 are some embodiments of the locking means used in connection with the switches shown in Figs. 1, 2 and 3.

In a preferred embodiment of my invention the insulating members of the compressed gas switch which carry the contacts are rotatably arranged on the grounded middle piece. The blades of the disconnecting switch forming the leads of the compressed gas switch contacts are arranged on the con-

tact cap. The fixed contacts of the disconnecting switch and the terminals are secured on sockets or the like behind the compressed gas switch, by way of example on the pressure air vessel, and may be separated from each other and from the compressed gas switch by means of fixed or movable insulating walls.

The rotatable insulating members carrying the contacts and the disconnecting switch blades are actuated by means of a single operating shaft and connecting rods, so that only a single operating mechanism is required for the disconnecting switches which are connected in front and to the rear of the compressed gas switch.

Referring first to Figs. 1 and 2, 1 and 2 are the movable and the fixed contacts of the compressed gas switch respectively. 9 is a grounded middle piece surrounding the mid-portion of the movable contact 1 and an insulating pipe 10 through which the movable contact rod 1 extends. 7 and 12 are flanges rotatably mounted on the middle piece 9 preferably by means of ball bearings 8. The upper flange 7 carries an insulating socket 6 forming part of the switch casing carrying the fixed contact 2. The disconnecting blade 4 and the knife blade contact 5 are secured to the contact member 2. The lower flange carries an insulating socket 13 transversed by the contact rod 1 to which the line terminal cap 14 of a disconnecting blade 15 and a knife blade contact 16 are secured. In Figs. 1 and 2 the blades of the disconnecting or isolating switches are shown in their closed position in which the blades 4 and 15 rotate about the longitudinal axis of the switch casing and engage fixed disconnecting switch contacts 21 and 24 respectively. The contacts 21 and 24 are mounted along an axis substantially parallel to that of the switch casing are supported by sockets 20 and 23 arranged on the compressed gas vessel 19 and are connected to leads 22 and 25 respectively. The compressed gas is supplied to the switch from the vessel 19 by means of a valve 18. 27 is a gas channel connecting the middle pieces 9 of the single poles so that the compressed gas may be supplied centrally on 100

the middle pole. The entire apparatus may be mounted on U-irons carrying the same. 17 is an insulating rod actuating the movable contact member 1. 11 is an actuating rod rotating the flange 7 together with the socket 6, the contact 2 and the blade 4. The lower flange 12, the lower socket 13 and the lower blade 14 are actuated by means of a rod 26 in an analogous manner. The rods 11 10 and 26 are actuated simultaneously by means of an operating shaft 29 and levers 28.

In order to connect the contacts of a multiple-phase compressed gas switch in series and to ground by means of the blades of the 15 disconnecting switch in its open position the contacts of the pressure air switch carry in addition to the disconnecting switch blades knife blade contacts engaged by the blades in their open position, the third blade engaging 20 a grounding contact so that the contacts of the compressed gas switch are connected in series and to ground and may be touched without any danger.

In Fig. 2 the closed position of the disconnecting blades of each switch unit is 25 shown in full lines, while their opened position is shown in dotted lines. In the open position the lowest disconnecting blade of Fig. 2 engages a grounded contact 30, while 30 the two other disconnecting blades connect the three contacts 2 and the three contact caps 14 in series. In opening the disconnecting switches the knife blade contacts 5 and 16 provided on the middle and one of the 35 outer poles of the switch are rotated about 90° and engage the disconnecting blades of the adjacent poles respectively.

In order to prevent the actuation of the disconnecting switches in the closed position 40 of the compressed gas switch the actuating shaft 29 of the disconnecting switches may be locked with the actuating shaft of the compressed gas switch in such manner that the disconnecting switches can be actuated only 45 if the compressed gas switch is in its open position. Other locking means are described hereinafter in connection with Figs. 4 and 5.

Any suitable driving means as a pressure air drive, a magnet drive, a relay or the like 50 may be provided in order to actuate the compressed gas switch and the disconnecting switches. A single driving means may be provided actuating the compressed gas switch and the disconnecting switches simultaneously as well as separate driving means may be 55 provided for the switches. By way of example the compressed gas switch may be actuated by means of pressure air while the disconnecting switches may be actuated mechanically by means of bell-cranks or the like. 60 The current is fed to the compressed gas switch by means of the disconnecting blades so that in order to kill the compressed gas switch contacts only the sockets 6 and 13 are 65 to be rotated. The ball bearings 8 are pro-

vided in order to facilitate the rotation of the sockets and may be omitted.

In a further embodiment of my invention an auxiliary switch is provided shunting in its closed position the compressed gas switch 70 so that the auxiliary switch carries a portion of the load current. In order to interrupt the current the auxiliary switch is opened first so that the compressed gas switch interrupts the total current. In order to cut in the current the compressed gas switch is closed first and then the auxiliary switch preferably comprising a rotatably U-shaped disconnecting blade. The auxiliary switch is actuated by 75 means of insulating members.

Referring now to Fig. 3 a disconnecting switch shunting the compressed gas switch is provided. The disconnecting switch comprises knife blades 4 and 15 and a connecting bolt 31 substantially parallel to the axis 80 of the switch casing forming together a U-shaped switching member. 32 is a flange rotatably arranged within a cylinder 33. 34 is a driving means by which the flange 32 is rotated. The flange 32 carries an insulator 20 supporting the bolt 31 and the switch blades 4 and 15. The switch blades engage in their closed position current carrying contacts 5 and 16 secured to the sockets 6 and 13 of the compressed gas switch. Current is fed to the device by means of the leads 22 and 25. In the position of the contacts shown in Fig. 3 the disconnecting switch carries a portion 85 of the load current. The actuating means of the compressed gas switch and the disconnecting switch may be of any suitable type but should be locked in such manner that the auxiliary or disconnecting switch may be actuated only when the compressed gas switch 90 is in its closed position. By dimensioning the auxiliary switch in suitable manner the compressed gas switch is overloadable to any desired degree because the latter carries normally only a portion of the load current and the full load current only during the short 95 times of cutting in and out the current.

In order to lock the disconnecting switches and the compressed gas switch with respect to each other the movable contact member of the compressed gas switch may be provided with a profilated portion whereby the movable contact members of the disconnecting switches can be actuated only if the profilated member is in a predetermined position. Further by the profilation of the movable compressed gas switch contact member and by a corresponding shape of the sliding contacts cooperating with the movable contact member the closing of the compressed gas switch may be prevented when the disconnecting switches are in their open position. Instead of this the locking means may be arranged on the actuating shafts or these shafts may be actuated by a single actuating mechanism in such manner that the discon-

necting switches cannot be opened or closed when the compressed gas switch is in its closed position.

Referring now to Figs. 4 and 5 some embodiments of the locking means are shown which may be used in connection with the switches described above. In Fig. 4 the lower portion of the movable contact rod 1 of the compressed gas switch is profilated as indicated by 36, so that it has hexagonal cross section. 35 are contact fingers cooperating with the surfaces of the profilated rod. The contact fingers 35 are connected with the contact cap 14 and therefore, while the contact rod 1 is in its closed position, a rotation of the socket 13 and the flange 12 is prevented. Since the upper disconnecting switch in Fig. 1 is actuated by means of the same shaft 29 as the lower disconnecting switch, both disconnecting switches are locked when the contact fingers 35 engage the surfaces of the profilated rod portion 36. After the compressed gas switch has opened the contact fingers 35 engage the cylindrical portion of the rod 1 so that now the disconnecting switches may be actuated. If the disconnecting switches are in their open position the compressed gas switch cannot be closed because the profilated portion 36 cannot engage the contact fingers 35 in the open position of the disconnecting switches. By choosing a suitable length for the profilated portion 36 an opening of the disconnecting switches may be prevented before the contacts of the compressed gas switch have been withdrawn a predetermined distance from each other.

Referring now to Fig. 5 the movable contact rod 1 is provided with radial extensions 37 sliding in slots of a guiding piece 38 surrounding the contact rod 1. By way of example the guiding member 38 may be the contact cap 14 shown in Fig. 1. Therefore the contact cap 14 and the socket 13 cannot be rotated while the extensions 37 engage the slots of the guiding piece 38. After the contact rod 1 has been lowered sufficiently the extensions 37 come out of engagement with the slots of the piece 38 so that now the disconnecting switches may be actuated. It is obvious that the compressed gas switch cannot be closed when the disconnecting switches are opened.

If the compressed gas switch and the disconnecting switches are actuated simultaneously the gap between the contacts of the compressed gas switch in their open position may be relatively small while the air gaps required in order to prevent back discharges are provided by the disconnecting switches. Therefore the total height of the compressed gas switch may be decreased in comparison to a compressed gas switch of the usual type.

A further advantage of my invention consists in that the gas exhaust pipes may be

arranged on the hollow contacts without interfering with other parts of the switch.

The switches described herein may be advantageously used in iron-clad switching plants, for instance, the switches being arranged within a grounded metal supporting structure in a manner well known in the art. Access to the switches may depend in any suitable manner upon locking means connected to the grounding means of the switch blades 4 or 15 so that the interior is only accessible after the switch contacts are grounded and separated from the current leads 22 to 25. After gaining access the compressed gas switch may be touched since all parts of it are dead and grounded. If in this condition the compressed gas switch shall be actuated the profilated portions of the contact rod 1 should be adjusted in such manner that an actuation of the switch is allowed.

The rear portion of the switch comprising the current leads may be made separately accessible and if desired may be locked independently of the front side.

I wish it to be understood that I do not desire to be limited to the exact details of construction shown and described for obvious modifications will occur to a person skilled in the art.

In the claims affixed to this specification no selection of any particular modification of the invention is intended to the exclusion of other modifications thereof and the right to subsequently make claim to any modification not covered by these claims is expressly reserved.

I claim:

1. A switching device of the gas-blast type comprising a casing, relatively movable contacts cooperating within said casing, said casing providing a passage for a gas blast between said contacts upon separation thereof, line terminal structure at opposite ends of said casing arranged to connect with said contacts respectively, and isolating switch members coacting with said terminals and movable into and out of circuit controlling engagement.

2. A switching device of the gas-blast type comprising relatively movable contacts, a casing forming a gas passage within which said contacts are mounted, line terminal structure at opposite ends of said casing arranged to connect with said contacts respectively, and a pair of rotatably mounted isolating switch blades movable to isolating and connecting positions with respect to said terminal structure.

3. A switching device of the gas-blast type comprising relatively movable contacts, a casing forming a gas passage at one end of which said contacts coact, said casing including insulating members at opposite ends thereof, terminals arranged to connect with said contacts

respectively carried by said insulating members, an isolating switch member connected to each of said terminals, and means for rotating said insulating members and moving said switch members into open and closed circuit positions.

4. A switching device of the gas-blast type comprising a pair of relatively movable contacts, a casing at one end of which said contacts are mounted including an intermediate metallic grounded portion and a pair of insulating members rotatably mounted at the opposite ends of said portion, a terminal arranged to connect with a corresponding contact carried by each of said insulating members, and an isolating switch blade connected to each of said terminals, rotation of said insulating members causing movement of said switch blades to connecting and isolating positions respectively.

5. A switching device of the gas-blast type comprising a pair of relatively movable contacts, a casing forming a gas passage therefor having terminal structure at opposite ends thereof, said terminal structure including current carrying contacts connected to the aforesaid contacts respectively, supporting structure rotatably mounted about an axis substantially parallel to the axis of said casing, and a pair of interconnected switch members carried at the opposite ends of said supporting structure coacting with said current carrying contacts.

6. A multi-phase switching arrangement comprising a plurality of switch units each including a casing, relatively movable contacts mounted therein and a switch member mounted for rotatable movement on each of said casings, means grounding each of said switch units when in the open circuit position comprising a ground contact arranged to be engaged by one of said members, and contacts carried by said casings for interconnecting said switch members in the open circuit position.

7. In a switching and isolating device of the gas-blast type including a movable rod contact, a contact coacting therewith, a casing therefor, line terminal structure carried by said casing connected to said rod contact and coacting contact respectively, and isolating switch members rotatably carried by said casing and connected to said terminal structure, and means interlocking said rod contact with respect to said casing so that movement of said switch members to isolating position may take place only when said rod contact is in the open circuit position.

In testimony whereof I affix my signature.
60 SIGWART RUPPEL.
